ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

RATCHETING MECHANISM.

1,367,283.

Specification of Letters Patent. Patented Feb. 1, 1921.

Application filed June 26, 1916. Serial No. 105,988.

To all whom it may concern:

Be it known that I, ARTHUR SIMON, a citizen of the United States, residing at Milwaukee, in the county of Milwaukee and State of Wisconsin, have invented new and useful Improvements in Ratcheting Mechanisms, of which the following is a full, clear, concise, and exact description, reference being had to the accompanying drawing, 10 forming a part of this specification.

This invention relates to solenoid ratcheting mechanisms and the like wherein successive strokes of a solenoid plunger are required for the desired operation of a driven 15 part.

In practice there are numerous instances where a self controlling mechanism of such character would be very desirable but much difficulty has been experienced in providing 20 for satisfactory self control of such mechanisms due to the tendency of the proposed control means to curtail the strokes of the solenoid plunger or plungers.

The present invention has among its objects to overcome the aforesaid and other 25 difficulties met with in such mechanisms and to provide a self controlling mechanism wherein the solenoid plunger or plungers will be permitted attraction to the full extent thereof and will likewise be permitted 30 full return movement for successive strokes.

A further object is to provide a simple, compact and durable ratcheting mechanism of unit construction for ready attachment to 35 field rheostats and other devices.

Other objects and advantages of the invention will hereinafter appear.

One embodiment of the invention is illustrated in the accompanying drawing in 40 which,

Figure 1 is a front elevation of the mechanism;

Fig. 2 is a side elevation thereof;

Fig. 3 is a sectional detail view; and

45 Fig. 4 is a diagrammatic view showing one circuit arrangement for the mechanism.

In general the mechanism comprises a ratchet wheel 1 driving through a shaft 2 a pinion 3 in turn meshing with and driving 50 a gear 4 which constitutes the driven member, pawls 5 and 6 coöperating with said ratchet wheel, solenoids 7 and 8 to actuate said pawls respectively, and switches 9 and 10 to control said solenoids respectively, all

of said parts being carried by a unitary 55 frame 11.

The frame 11 is provided with supporting lugs 12, 13 and 14 for attachment to a panel or other suitable base and comprises magnetic material. It is so formed as to provide complete frames for the solenoids and an intermediate part for the support of the mechanical element specified. More specifically the frame is centrally bored to receive a stud or spindle 15 upon which the gear 4 is mounted in the rear of said frame while at its lower end said frame is provided with spaced bearings 16 and 17 (Fig. 2) for the shaft 2 carrying the ratchet wheel and pinion 3 and with a holding detent 18 for the ratchet wheel yieldable to said wheel when positively driven. The frame is recessed on opposite sides of a central portion to receive the solenoid windings and is provided with tubular extensions to receive the solenoid 75 plungers, said extensions having suitably fixed thereto non-magnetic collars 19 serving as "down" stops for said plungers.

The ratchet wheel is mounted on the shaft 2 directly back of the bearings 16 and the 80 pawls 5 and 6 (Fig. 3) are supported upon levers 20 and 21 loosely mounted upon said shaft immediately back of said ratchet wheel. The hubs of these levers are recessed to receive a coil spring 22, said spring 85 acting upon said levers to bias the same in opposite directions and both downwardly. The pawls are formed to straddle their respective levers and are connected thereto by pins 23 whereby they are permitted a rocking movement independently of their levers. Also, the pawls are connected by pins 24 to actuating links 25 adapted for connection to the plungers of the solenoids. Thus as will be apparent each pawl will tend to assume 90 the position of the right hand pawl (Fig. 1) and hence free the ratchet wheel, where- as a pull exerted upon its link will throw it into engagement with said ratchet wheel and thereupon rotate both about the axis of 100 shaft 2.

The solenoids are of like construction, and referring to the solenoid shown in section, the same includes a winding secured in the frame in the usual manner by a brass 105 tube 26, a movable plunger 27 connected to link 25 and an auxiliary plunger 28 pro- vided with a threaded extension 29 for con-

nection to control switch 9 as hereinafter described. The main plunger is provided with a non-magnetic cap 30 centrally riveted thereto to prevent sticking of said plunger 5 to the magnet frame and the magnet frame is provided with a non-magnetic bushing 31 surrounding the auxiliary plunger to prevent the latter from sticking to said frame.

The two control switches are also of like 10 construction and describing that of the solenoid just described, the same includes (Fig. 2) two relatively stationary contact fingers 32 and 33 suitably mounted upon the frame 11 and a movable bridging contact 34. The 15 bridging contact comprises a tube mounted upon and insulated from a spindle 35 carried by and between bifurcated parts of a bell crank lever 36 (Fig. 1). The lever 36 is supported upon a spindle 37 carried by 20 and between extensions 38 of the supporting frame, said lever and extensions having co-operating parts 40 and 41 to limit the movement of the former in both directions. The end of the lever is connected to the ex- 25 tension of the auxiliary plunger 28, said connection comprising a block 42 attached to said lever and into which the extension threads for purposes of adjustment. Thus attraction of the auxiliary plunger tends to 30 move the bridging contact from engagement with the stationary contacts while said lever is provided on opposite sides of the stationary contacts with weights 43 and 44 tending to effect engagement of said contacts and in consequence tending to raise 35 the auxiliary plunger of the solenoid.

As will be understood each switch provides for making and breaking the circuit of its respective solenoid and in consequence 40 each solenoid upon responding tends through its main plunger to actuate the ratchet wheel and through its auxiliary plunger to interrupt its own circuit. It will be observed, however, that the inertia of the weighted 45 switch lever opposes the attraction of the auxiliary plunger while on the other hand the self induction of the solenoid retards the building up of its flux during the movement of the main plunger. Accordingly with the 50 relation of parts illustrated only a comparatively few magnetic lines of force initially stray through the auxiliary plunger so that the weight and inertia of the switch parts may be relied upon to restrain the auxiliary plunger until the main plunger reaches its limit of travel. Thereupon the 55 magnetism rises to its full value with a resultant increase in the magnetic lines of force through the auxiliary plunger to attract the same and open the control switch 60 for deenergization of the solenoid. Thereby full attraction of the main plunger is insured to insure a full step of movement of the ratcheting mechanism. Here it is to be 65 noted that attraction of the auxiliary

plunger as described does not move the switch lever to its full extent and that said lever is thereafter capable of further movement in the same direction prior to arrest by its stops 41. Also, it is to be noted that 70 the degree of movement of the switch lever by attraction of the auxiliary plunger and the normal position of said plunger in the magnetic field of the solenoid may be varied as desired by the adjustable connection between such lever and plunger. 75

When the solenoid is deenergized and its main plunger makes its return stroke, the residual magnetism, eddy currents and inertia of the switch parts cause the auxiliary 80 plunger to follow the main plunger until the former is checked by its down stops 41 or at least until it has moved an appreciable distance. This provides a time element in the reclosure of the control switch in addition to the inherent time element of the switch due to the separation of its contacts and as will be apparent the inertia of the switch parts and of the auxiliary plunger tends to prolong such additional time ele- 85 90 ment. Accordingly a substantial time element is thus provided for the return stroke of the solenoid plunger which by reason of its weight and that of its connected parts acquires sufficient momentum to insure a 95 full return stroke thereof prior to re-attraction even though the solenoid circuit be re-closed slightly prior to completion of such stroke. Moreover, the self induction of the solenoid would further delay re-attraction 100 of the plunger, under such conditions.

Thus upon completion of the circuit of either solenoid, assuming the circuit connections to be as illustrated in Fig. 4, a step by step movement of the driven member 105 may be obtained and continued automatically until the circuit is permanently opened by a suitable control switch S. Also, as will be understood, the two solenoids provide for reverse operations of the driven member se- 110 lectively.

As illustrated, the mechanism is particularly adapted for operating field rheostats, the same being adapted to be attached to the rear of the panel carrying such rheostat and 115 its driven gear 4 being provided with suitable lugs 45 to interlock with the rheostat part to be operated.

It is, of course, to be understood that the invention is susceptible of various modifications falling within the scope of the appended claims. 120

What I claim as new and desire to secure by Letters Patent is:

1. In combination, a member to be operated, a solenoid having a reciprocable plunger, an operative connection between said member and said plunger providing for a step by step operation of the former upon successive reciprocations of the latter 130

- and means mechanically free from said plunger for intermittently energizing and deenergizing said solenoid after completion of the strokes of said plunger, said means 5 being associated with said solenoid to be electromagnetically controlled thereby.
2. In combination, a member to be operated, a solenoid having a reciprocable plunger, an operative connection between said 10 member and said plunger providing for a step by step operation of the former upon successive reciprocations of the latter and means to intermittently energize and deenergize said solenoid, said means being electromagnetically controlled by said solenoid 15 and being mechanically free from said plunger but subject to control thereby to delay energization and deenergization of said solenoid pending completion of the 20 strokes of said plunger.
3. In combination, a member to be operated, a solenoid for operating said member by successive strokes of its plunger, and a circuit making and breaking device for 25 said solenoid electromagnetically controlled thereby to permit a full stroke of the solenoid plunger prior to interruption of circuit and magnetically controlled for delay in re-establishment of circuit.
- 30 4. In combination, a member to be operated, a solenoid for operating the same by successive strokes of its plunger, and a circuit making and breaking device for said solenoid having an actuating part in the 35 magnetic field of said solenoid but responsive only after a full stroke of the solenoid plunger, said actuating part also tending by magnetic attraction to follow the plunger of said solenoid after interruption of the 40 current supply to the latter, to thereby delay reestablishment of circuit.
5. In combination, a member to be operated, a solenoid having a main plunger to actuate said member and an auxiliary plunger, and a circuit making and breaking device for said solenoid controlled by said auxiliary plunger, said auxiliary plunger being responsive to effect interruption of circuit but only after full stroke of said 45 main plunger and being subject to further movement in attracted direction upon the return stroke of said main plunger to delay the reclosure of the circuit of said solenoid.
- 50 6. In combination, a member to be operated, a solenoid to be intermittently energized to operate said member, said solenoid
- having a main plunger for actuating said member and an auxiliary plunger, and a circuit making and breaking device for said solenoid connected to said auxiliary plunger 60 to be actuated thereby for interrupting circuit and being weighted for opposing attraction of said auxiliary plunger and for restoration to circuit closing position, said auxiliary plunger being disposed in the 65 magnetic field of said solenoid to be attracted only after full attraction of said main plunger and being subject to attraction to said main plunger during the return stroke thereof to thereby delay reestablishment of circuit by said device.
7. In a solenoid operated mechanism, in combination, a solenoid having a plunger, a circuit controlling switch therefor biased to one position, and an operative connection 75 between said switch and solenoid including a magnetic part arranged within the magnetic field of said solenoid for attraction to operate said switch against its bias but only after full attraction of said 80 plunger, said magnetic part being subject to arrest by said plunger and also to continued movement thereby through magnetic attraction, when said plunger is released upon deenergization of said solenoid, where- 85 by the return of said switch to normal position is delayed pending full return movement of said plunger.
8. In a solenoid operated mechanism, in combination, a solenoid having a reciprocable plunger, a circuit making and breaking switch therefor biased to closed position, an operative connection between said switch and said solenoid including a magnetic part arranged within the magnetic 90 field of said solenoid for attraction to open said switch, but only after full attraction of said plunger, said magnetic part being subject to arrest by said plunger and also to continued movement therewith due to the 100 magnetic attraction therebetween, when said plunger moves away from attracted position and means limiting such continued movement of said magnetic part to thereby insure release of said switch, but permitting 105 sufficient continued movement of said magnetic part to enable full return movement of said plunger prior to reclosure of said switch.

In witness whereof, I have hereunto sub- 110 scribed my name.

ARTHUR SIMON.
